UNITED STATES PATENT OFFICE.

MAX JAHN, OF LEIPSIC-PLAGWITZ, GERMANY.

STOVE.

SPECIFICATION forming part of Letters Patent No. 522,015, dated June 26, 1894.

Application filed June 5, 1893. Serial No. 476,620. (No model.)

To all whom it may concern:

Be it known that I, MAX JAHN, a subject of the King of Saxony, and a resident of Leipsic-Plagwitz, in the Kingdom of Saxony, German Empire, have invented a new and Improved Stove with Heating-Spirals, of which the following is an exact specification.

My invention relates to a stove with heating spirals and has for its purpose to utilize the fuel and the heating-gases in a higher degree than is the case in the stoves constructed hitherto.

In order to make my meaning clear, I refer to the accompanying drawings, in which similar letters indicate similar parts, and in which—

Figure 1 is a longitudinal section of the under part of my improved stove. Fig. 2 is a section of Fig. 1 on line G H. Fig. 3 is a longitudinal section of a modified stove. Fig. 4 is a section of Fig. 3 on line E F. Fig. 5 shows a longitudinal section of Fig. 3 on line M N. Fig. 6 is a section of Fig. 3 on line C D. Fig. 7 is a section of Fig. 3 on line A B.

In carrying my invention into effect, I construct my stove in such a manner, that the heating-spirals begin from the base of the stove and reach to the cap of the same, so that the whole surface of the stove is effective for the heating of the room.

Y is the fire-chamber, from which the heating-gases arise, as is shown by the full arrows in Figs. 1 and 3 of the drawings.

R and S are the outer spirals, wound around the middle tube L serving for the circulation of the air and provided with an inner spiral I. While the spiral S receives the gases arising from the fire-chamber Y, the spiral R contains the air to be heated by the spiral S.

k' are openings at the base of the stove through which the air enters the tube L from below.

w' at the upper part of the stove is the outlet for the air heated within the tube L.

The openings k, on the right side of Figs. 1 and 3, serve for the entrance of the cold air, which leaves the stove by passing through the openings w, opposite to the openings k, in order to enter the room to be heated.

O is the chimney-funnel for the eduction

of the heating-gases which come from out the heating-spiral S, after having been utilized.

The manner of operation of the described stove is the following: The heating-gases evolved in the fire-chamber Y enter the spiral S, as shown by the full arrows in Figs. 1 and 3 of the drawings and heat the air circulating in the spiral R in a perfectly regular manner as well as the air in the tube L, which assumes a helicoidal movement by rising in the inner spiral I. The cold air entering the stove by the openings k as indicated by the dotted arrows, leaves the same, when heated, by passing through the openings w on the opposite side of the stove, as is illustrated by the half dotted arrows in Figs. 1 and 3. By the spirals R and S, reaching from the base to the top of the stove, the whole surface of the latter is utilized for the heating of the room. The cold air lying generally on the floor of the room is sucked by the tube L through the openings k', whereby a regular and quick heating of the room is effected.

The modification shown in Figs. 3 to 7 only differs from the stove in Figs. 1 and 2 by the arrangement of the outer-hearth while the construction of the spirals R, S and L is similar to that of the stove in Figs. 1 and 2.

Having now fully described the nature of my invention, what I desire to secure by Letters Patent of the United States is—

1. In a stove, the combination of a centrally-arranged tube L, a spiral I arranged within said tube, air-inlet openings communicating with the lower end of said tube, air-outlet openings communicating with the upper end of the tube, spirals R and S arranged around the tube L, and extending from the base of the stove to the upper end thereof, air inlet and outlet openings communicating with the spiral R, a fire chamber communicating with the lower end of the spiral S and an outlet for the products of combustion communicating with the upper end of the spiral S as specified.

2. In a stove, the combination of a centrally-arranged vertical tube L, a spiral I arranged vertically within the tube L, an air inlet opening in the base of the stove and communicating with the lower end of the tube

L, an air-outlet opening communicating with the upper end of the tube, spirals R and S arranged around the tube L and extending from the base to the top of the stove, a series of air inlet openings communicating with the spiral R at different points in the height thereof, air-outlet openings communicating with said spiral R opposite to the inlet openings a fire chamber Y communicating with the lower end of the spiral S, and an outlet O communicating

with the upper end of the spiral S, as and for the purpose specified.

In testimony whereof I have signed this specification in the presence of two subscribing witnesses.

MAX JAHN.
